UNITED STATES PATENT OFFICE.

HOWARD E. WATKINS, OF SUMMIT, NEW JERSEY.

DESIGN FOR A GLOBE OR SIMILAR ARTICLE.

43,074.

Specification for Design.

Patented Sept. 24, 1912.

Application filed July 11, 1912. Serial No. 708,887. Term of patent 7 years.

To all whom it may concern:

Be it known that I, HOWARD E. WATKINS, a citizen of the United States, residing at Summit, in the county of Union and State of New Jersey, have invented a new, original, and ornamental Design for Globes or Similar Articles, of which the following is a specification, reference being had to the accompanying drawing, forming part there-

of, and showing a side elevation of a globe or similar article bearing my new design.

I claim:

The ornamental design for a globe or similar article as shown.

HOWARD E. WATKINS.

Witnesses:

EDWARD L. COX,
HERMAN GUSTOW.
